UNITED STATES PATENT OFFICE.

JAMES K. PUTNAM, OF TULSA, OKLAHOMA, ASSIGNOR TO THE INTERNATIONAL DERRICK & EQUIPMENT COMPANY, OF COLUMBUS, OHIO.

SUPPORTING MEANS FOR WELL TUBING.

Application filed July 28, 1927, Serial No. 209,145. Renewed March 26, 1929.

The invention relates to apparatus or mechanism used in oil wells.

One of the objects of my invention is to provide a supporting device for well tubing which is adapted to automatically grip the sides of the well whenever the lower end of the tubing structure is caused to contact with or rest to a substantial extent upon the bottom of the well.

Another object of my invention is to provide such a device that the breaking of the tubing either above or below the supporting device will automatically cause the supporting device to grip the sides of the well with sufficient firmness to preclude material falling action.

Other objects of my invention will appear as this description progresses and will be more or less accentuated by the claims appended hereto.

My invention preferably takes the form of a supporting member carrying a plurality of slips designed to be automatically expanded under given conditions, so that they will be caused to grip the sides of the well. These slips are preferably so mounted that they are normally locked against accidental expansion. In order to effect this safeguard against accidental actuation of the slips, I preferably provide slips which must be initially released from locked position and then forced outwardly in a lateral manner so as to bring them into gripping contact with the sides of the well.

My supporting device is further preferably constructed so that it may be introduced into a string of tubing and, when in position therein, will be free from leakage. I preferably accomplish this by having contacting shoulders mounted on relatively telescoping parts of my structure.

Another feature of my invention consists in the provision of means for limiting the outward movement of the slips in order to prevent escape of such slips from the support upon which they are mounted and in order to prevent gripping the sides of the well with undue force.

Another feature of my invention consists in the provision of a means for actuating the slips which embodies a means for first moving the slips laterally and then longitudinally together with means for directly applying spring pressure to these slips.

Still another aspect of this particular struc-

ture arises from the fact that I have provided a spring member for normally tending to further telescope the members of my supporting device together with a means for positively stopping the extension of such members with relation to each other before the spring is over-stressed. This stopping means simultaneously effects a shoulder contact which obviates leakage.

With the foregoing in view, the invention resides in the novel subject matter herein-after described and claimed, the description being supplemented by the accompanying drawings.

Fig. 1 is a vertical sectional view partly in elevation showing the relation of parts when the tubing is being lowered down the well, or prior to such lowering.

Fig. 2 is a sectional view with the parts related as shown in Fig. 1.

Fig. 3 is a view similar to Fig. 2 but showing the tubing supported in the well casing.

Fig. 4 is a horizontal sectional view on line 4—4 of Fig. 3.

Fig. 5 is a side elevation of the upper tubular member.

Fig. 6 is an upper end view of this member.

Fig. 7 is a side elevation of the lower tubular member.

Figs. 8 and 9 are respectively, a side elevation and an end view of one of the slip-connecting springs.

The form of construction selected for illustration will be herein rather specifically described, with the understanding however that within the scope of the invention as claimed, numerous variations may be made.

10 denotes an upper tubular member threaded at its upper end as at 11, for connection with a tubing section 12. The lower end of the tubular member 10 is enlarged both internally and externally and is provided at its interior with an annular upwardly facing shoulder 13, which is formed by the upper end of a tubular extension 14 on a cylindrical spring barrel 15, said tubular extension being threaded into the lower end of the member 10. The spring barrel 15 projects to any desired extent, below the member 10 and is provided at its lower end with an upwardly facing shoulder formed by a ring 16 secured to the barrel by fasteners 17. This barrel is spaced around a lower tubular member 18 whose lower end is threaded as at 19 for engagement with a lower tubing section, and the upper

end of said member 18 passes slidably through the tubular extension 14 of the spring barrel 15, into the lower portion of the upper tubular member 10. The upper end of member 18 is provided with an annular peripheral enlargement 20 which rests on the shoulder 13 when the weight of all parts below the member 10, is suspended by this member and parts above the latter. This relation is seen in Figs. 1 and 2, and when it exists, a second peripheral enlargement 21 on the lower member 18, is spaced below the extension 14. However, when member 10 slides downwardly, the enlargement 21 enters the lower end of the extension 14 and the latter rests on a collar 23 as shown in Fig. 3, thereby limiting the downward sliding of said member 10.

The collar 23 is threaded or otherwise secured around the member 18 and it may well abut the lower side of the enlargement 21 of said member. Another collar 24 surrounds the member 18 and contacts with the lower side of the collar 23, and a coiled compression spring 25 is positioned between the spring barrel 15 and the member 18 with its upper end in contact with said collar 24, while its lower end abuts the collar 16.

A slip actuating means in the form of a sleeve 26 surrounds the upper portion of the spring barrel 15 and the lower end portion of the member 10, the upper end of said sleeve terminating at the shoulder 27 formed at the juncture of the two external diameters of said member 10. The lower end of this sleeve 26 is connected by appropriate fasteners 28 with the collar 24, said fasteners being passed through slots 29 in the spring barrel 15. The function of this sleeve will be hereinafter explained.

Above the shoulder 27, the member 10 is provided with a plurality of cams or cam lugs 30 which are spaced apart both vertically and circumferentially of said member, the peripheral surfaces of these cams being disposed almost in vertical planes. All of these cams however, except the lowermost have additional cams 31 at their lower ends which incline outwardly from the center of the member 10 and are at obtuse angles to the peripheral faces of said cams 30. The lower ends 31^a of the lowermost of the cams 30 are preferably at approximately right angles to the axis of the member 10. Formed at the upper ends of the uppermost cams 30, are a plurality of overhanging stop hooks 32 for a purpose to appear.

A plurality of slips 33 are disposed at the periphery of the member 10 and are internally cut away to quite an extent, giving maximum space through which fluid may pass. Between its ends, each slip is provided with a cam portion 34 normally engaging an intermediate one of the cams 31. At its upper end said slip is provided with an acute angular portion 35 normally engaging an uppermost of the cams

31, and at its lower end, said slip is provided with a hook portion 36 normally underlying the lower end 31^a of one lowermost cam 30. This lower end of the slip 33 is provided also with a surface 37 which inclines toward the axis of the member 10 and normally overlies the upper end of the sleeve 26 as shown in Figs. 1 and 2. At the inner extremity of this cam surface 37, the slip is provided with a shoulder 38.

While lowering the entire device into a well, the slips 33 are held in the positions of Figs. 1 and 2 by means of U-shaped springs 39 which are positioned between the slips and the member 10 as shown most clearly in Fig. 4, the arms of said springs being provided with hooks 40 hooked into appropriate openings in the slip portions 34.

As soon as the lower tubular member 18 reaches the limit of its downward movement, the upper member 10, the slips 33, the spring barrel 15 and the collar 16, all move further downward, but during such movement, the spring 25 maintains the collar 24 in contact with the collar 23 and hence the sleeve 26 is held against any descent other than downward yielding. The result is that as the slips 33 move downwardly, their cam surfaces 37 slide outwardly upon the upper end of the sleeve 26, thus unhooking the means 36—31^a. As the member 10 now moves further downwardly within the slips, the cams 31 first project the slips rather rapidly toward the well casing. Then, the more forcible cams 30 come into play to expand said slips with greater power and cause them to tenaciously bite the casing, thus effectively supporting the member 10 and all parts connected with the upper end of the latter.

If the downward movement of the member 10 be sufficient, the stops 32 will directly engage the upper ends of the slips 33 as shown in Fig. 3. This relation will also exist when withdrawing the entire apparatus from the well casing, and at that time, the stops 38 contact with the sleeve 26 and hold the slips 33 against any excessive outward movement.

It will be seen from the description above that I have provided a structure having a number of important advantages. For one thing, I have provided slips which are locked against accidental movement but which may be released from such locked position and then projected into gripping contact with the sides of the well by what constitutes, practically, one continuous motion. Furthermore, these slips are both limited against excessive outward movement and protected against accidental frictional contact by means of the hook-like projection 32.

There are a number of other features of my invention which are important from a practical standpoint. Another feature of this device results from the fact that the tubular sections are respectively provided with a

shoulder 20 and a seat 13 therefor to produce a normally fluid-tight connection between said sections. This shoulder and seat, likewise, serve to limit the extent to which 5 the spring 25 is stressed. A still further feature consists in the fact that the slips are so mounted upon their supporting means that they are self-supporting and will not drop out of such supporting means either when 10 breakage occurs immediately beneath the slips or when the tubing support is out of the well and the weight removed therefrom.

I claim:—

1. A tubing supporting assembly comprising upper and lower tubular members slidably connected with each other to permit further downward movement of the upper member when the lower member reaches a downward limit, normally retracted slips 20 around said upper member, means for projecting said slips when the latter are held and said upper member moves downwardly, a thrust shoulder on the periphery of said lower member, a thrust collar slidably 25 rounding said lower member below said thrust shoulder, means connecting said thrust collar with said upper member, a coiled compression spring interposed between said shoulder and said collar, and slip-actuating 30 means supported by said spring, said slip-actuating means extending between the upper end of said spring and said slips.

2. A tubing supporting assembly comprising upper and lower tubular members slidably connected with each other to permit further downward movement of the upper member when the lower member reaches a downward limit, normally retracted slips around 35 said upper member, means for projecting said slips when the latter are held and said upper member moves downwardly, a spring barrel connected with the lower end of said upper member and projecting downwardly therefrom around said lower member, said barrel 40 having an internal upwardly facing shoulder at its lower end, and a vertical slot near its upper end, a collar on said lower member within the spring barrel, a coiled compression spring within said spring barrel and interposed between said shoulder and said collar, a slip-actuating sleeve around said upper 45 member and the upper end of said spring barrel, and connecting means between said sleeve and said spring, embodying a portion passing 50 through the aforesaid slot.

3. In a tubing supporting assembly, a tube having external cams, each cam being formed with a peripheral face converging downwardly with the axis of said tube and disposed at 55 an extremely acute angle to said axis, each cam also having an abrupt lower end face declining inwardly from the lower end of said peripheral face; and slips mounted around said tube, each slip having an inwardly projecting lug provided with an upper end face

inclined uniformly with and normally abutting said lower end face of one of said cams, said lug being provided also with an inner side face extending downwardly from said upper end face and inclined uniformly with 70 said peripheral face of the cam, said end faces being co-operable in effecting quick projection of the slips upon initial downward movement of the tube within said slips, the other faces being then co-operable to effect forcible 75 outward movement of the slips upon further depression of the tube.

4. In a tubing supporting assembly, a body, casing-engaging slips at the periphery of said body, means for outwardly forcing said slips 80 upon relative vertical movement of said slips and body, interhooked means on said slips and body normally preventing said relative vertical movement thereof, said means being releasable by slight outward shifting of said 85 slips, and means for effecting said slight outward shifting.

5. In a tubing supporting assembly, a body, casing-engaging slips at the periphery of said body, means for outwardly forcing said 90 slips upon relative vertical movement of said slips and body, interhooked means on said slips and body normally preventing said relative vertical movement thereof, said means being releasable by slight outward shifting 95 of said slips, downwardly facing cams on the lower ends of said slips inclining toward said body, a sleeve whose upper end abuts said cams, and means for holding said sleeve while the body moves downwardly, causing said 100 cams to outwardly shift said slips and release said interhooked means.

6. A structure as specified in claim 5; together with stops at the inner extremities of said cams to abut the sleeve and limit projection of the lower ends of the slips when the assembly is out of the well, and stops on said body to engage the upper ends of said slips and hold them against excessive outward movement.

7. In a tubing supporting assembly, a body having circumferentially spaced cams, slips spaced from the body and engaging said cams, and springs between said slips yieldably connecting adjacent slips and effective 115 to retract said slips.

8. In a tubing supporting assembly, a body having circumferentially spaced cams, slips spaced from the body and engaging said cams, and substantially U-shaped springs between said slips having hooks at their ends connected with said slips to yieldably connect adjacent slips with each other.

9. Apparatus for supporting tubing comprising a supporting element, slips carried by said element, means for normally locking said slips thereon against accidental movement, and means for automatically releasing said locking means whenever either end of the tubing is relieved of substantial pulling force.

10. A supporting device for well tubing comprising slips, means for supporting said slips, means for forcing said slips laterally outward upon relative longitudinal movement between said slips and said supporting means, means for normally locking said slips against such longitudinal movement, and means for automatically unlocking said slips to permit said longitudinal movement whenever either end of the tubing is relieved of substantial pulling force.
11. A supporting device for well tubing comprising slips, means for supporting said slips, means for forcing said slips laterally outward upon relative longitudinal movement between said slips and said supporting means, means for initially locking said slips against such relative longitudinal movement, and means for moving said slips laterally to release them from such locked position.
12. Apparatus for supporting tubing comprising telescoping tubular sections, slips carried by one of said telescopic tubular sections, a spring exerting pressure which will be effective to telescope said sections whenever substantial pull is removed from either

end thereof, and means for moving said slips longitudinally, said means being directly mounted upon said spring independently of the lower telescoping section.

13. Apparatus for supporting tubing comprising telescoping tubular sections, slips carried by one of said telescopic tubular sections, said slips being movable longitudinally with relation to said slip-carrying means, means for moving said slips laterally to grip the sides of the well as the result of said longitudinal movement, and a single means for limiting both longitudinal and lateral movement of said slips.

14. Apparatus for supporting tubing comprising a slip-carrying means embodying cam-lugs, slips having sockets by which they are carried by the cam-lugs when said slips are in retracted position, said slips being movable longitudinally with relation to said slip-carrying means, and means for effecting such relative longitudinal movement.

In testimony whereof I have hereunto affixed my signature.

JAMES K. PUTNAM.
